UNITED STATES PATENT OFFICE.

DAMON BALE, OF LOUISVILLE, KENTUCKY, ASSIGNOR TO STANDARD SANITARY MANUFACTURING CO., OF PITTSBURGH, PENNSYLVANIA, A CORPORATION OF NEW JERSEY.

PIPE-BRACKET.

1,283,451.

Specification of Letters Patent.

Patented Nov. 5, 1918.

Application filed August 3, 1917. Serial No. 184,257.

To all whom it may concern:

Be it known that I, DAMON BALE, a citizen of the United States, residing at Louisville, county of Jefferson, and State of Kentucky, have invented a new and useful Pipe-Bracket, of which the following is a specification.

This invention relates to pipe brackets adapted to be attached to factory wash sinks for the purpose of supporting water supply pipes thereover, although they may be found of service in other connections.

The usual method of attaching pipe supporting brackets to sinks, is by means of bolts, holes being drilled in the flange of the sink to correspond with like holes in the base of the bracket. This practice is objectionable for several reasons; the flange is apt to be broken in the drilling; if the sink is enameled, the enamel will be chipped off, leaving an entrance for moisture, resulting in rust and further loosening of the enamel. The drilling can not well be done at the factory, as it is not known on which side the sink the purchaser will wish to place the brackets.

An object of this invention is to provide a bracket as characterized which may be securely attached to a sink at any point along its brim, without perforating the flange, or damaging the enamel.

With the foregoing and other objects in view, the invention has particular relation to certain new and novel features of construction illustrated in the accompanying drawings, which form a part of this specification, wherein is set forth an embodiment of the invention, but it is to be understood that such changes and modifications may be resorted to as come within the scope of the appended claims.

Referring to the drawings, wherein similar reference numerals designate like parts in the several views; Figure 1, is a perspective view of a factory wash sink to which brackets embodying my invention are attached; Fig. 2, a front elevation, on an enlarged scale, of a bracket adapted to carry two lines of pipe; Fig. 3, a side elevation of Fig. 2; Fig. 4, a central vertical section of a bracket adapted to carry one line of pipe; Fig. 5 a bottom plan view of Fig. 3; and Fig. 6, an elevation of a modified form adapted to span a sink and support the pipes centrally thereover.

In the drawings I have illustrated a factory wash sink —10— of conventional design, which is provided with an overflow pipe —11—, and has a lateral flange, or rim —12—, to which are attached brackets 60 —14— which are adapted to support water pipes —15, 16—, for the delivery of hot and cold water. The brackets each comprise a base —17—, of suitable length, and of such breadth as to accommodate a slot, or recess —18— extended in from the forward side thereof. The depth of the slot is substantially the same as the width of the sink flange. The ceiling —19— of the slot is contoured to fit the upper surface of the 70 flange. The floor of the slot is provided with a plurality of perforations —20— therethrough. Lugs —21—, integral with the floor, are positioned on each side of the perforations 20, and spaced therefrom a 75 suitable distance to receive between them screw-threaded nuts —22— and hold them in alinement with the perforations. Set screws —23— extend through the perforations and are engaged in the nuts. The distance between the upper surface of the nuts and the roof of the slot is such as to receive the flange of the sink. A back —24—, comprising a thin web, extends from the rear of the base, the sides thereof converging to a 85 connection with a bearing —25—, which is provided with a bore for the reception of pipe. A second bearing —26— may be positioned above the first mentioned one. Flanges —27— skirt the edges of the back, projecting forward therefrom, stiffening same and assisting in the support of the bearing. The roof of the slot may be extended forward, and curved upward to form a receptacle —28—, in which soap may be placed. This 90 receptacle is provided with a perforation —29— which serves to drain it, leading the drainage into the sink. The flanges 27 may be carried forward, as at —30— to form sides for the receptacle.

To place the bracket in position on a sink, the set screws are adjusted so that their ends will be flush with the upper surface of the nuts. The flange of the sink is then entered in the slot, the bracket slid along 105 on the flange until the proper position is reached, and then the set screws are tightened up against the bottom of the flange. The bracket as described may be cast integrally, the perforations 20 and 29, and the 110

bearings for the pipes being cored. Thus no machine work is required—and the brackets may be produced very cheaply. The nuts and set screws are commercial articles, which may be purchased at a low price as they are manufactured by automatic machines which turn them out rapidly and in large quantities. In Fig. 6, I have illustrated a modified form of support, in which my new means of attachment is utilized, by means of which the water pipes may be supported over the center of the sink, whereby both sides of the sink may be used at the same time. This modification is applied by sliding it on the flanges from the end of the sink.

It will be observed that my improved bracket has a wider range of usefulness than the ordinary bracket, used for the same purpose, as it can be attached to a sink at any point in its length, and on either side, without any special preparation of the sink, such as is required for the ordinary bracket.

Having thus described my invention so that any one skilled in the art pertaining thereto may make and use the same.

I claim:—

1. In a device as characterized, a base having a slot extended in from the side thereof, the floor of the slot having a perforation therethrough, a lug on each side of the perforation, a screw threaded nut positioned between said lugs, a set screw extended through the perforation and engaged in the nut, and the roof of the slot extended forward to form a receptacle.

2. In a bracket as characterized, a base having a slot extended in from a side, the ceiling whereof is contoured to conform to the upper surface to which it is to be applied, a web extended upward from the roof of the slot and carrying a bearing, the floor of the slot having a smooth walled perfora-

tion therethrough, a lug disposed on each side of said perforation at right angles to the forward edge of the slot, a screw threaded nut removably disposed between said lugs, and a set screw extended through the perforation and said nut and adapted to bear against an object placed between it and the ceiling of the slot.

3. In a bracket as characterized, a base having a slot extended in from a side thereof the ceiling whereof is contoured to conform to the object to which it is to be applied, the roof of the slot being extended forward to form a receptacle, a standard erected on the roof and forming the rear wall of the receptacle, the floor of the slot having a smooth walled perforation therethrough, a screw threaded nut in alinement with said perforation, a set screw extended through the perforation and said nut and adapted to bind against the object placed between it and the ceiling of the slot.

4. In a bracket as characterized, a base having a slot extended in from a side thereof, the ceiling whereof is contoured to conform to the object to which it is to be applied, the floor of said slot having a smooth walled perforation therethrough, a lug disposed on each side of said perforation at right angles to the forward edge of the floor, a screw-threaded nut removably disposed between said lugs, a web extended upward from the rear of the base, a bearing on the end of said web adapted to receive a pipe, a flange skirting the edges of and extending forward from the web, the upper portion of the base extended and contoured to form a receptacle, and a set screw extending through the perforation in the floor and through said nut being operatively engaged with the nut.

DAMON BALE.
